UNITED STATES PATENT OFFICE

158,304

CUP OR SIMILAR ARTICLE

Patricia J. McGough, Pasadena, Calif.

Application June 28, 1948, Serial No. 147,252

Term of patent 3½ years

(Cl. D44—9)

To all whom it may concern:

Be it known that I, Patricia J. McGough, a citizen of the United States, residing at Pasadena, in the county of Los Angeles and the State of California, have invented a new, original, and ornamental Design for a Cup or Similar Article, of which the following is a specification, reference being had to the accompanying drawing, forming a part thereof.

The dominant features of the design reside in the portion of the cup drawn in full lines as shown.

I claim:

The ornamental design for a cup or similar article, as shown and described.

PATRICIA J. McGOUGH.
